IP LLP(57) **CLAIM**

The ornamental design for an orientation washer, as shown and described.

DESCRIPTION

FIG. 1 is a top perspective view of an orientation washer incorporating my new design;
 FIG. 2 is a bottom perspective view thereof;
 FIG. 3 is a top plan view thereof;
 FIG. 4 is a rear view thereof;
 FIG. 5 is a bottom plan view thereof;
 FIG. 6 is a left side view thereof;
 FIG. 7 is a front or rear view thereof; and,
 FIG. 8 is a top perspective view thereof shown in an environment of use with an unclaimed threaded cap and threaded post.
